UNITED STATES PATENT OFFICE.

FRED E. DERRICK AND SOLOMON C. BROTT, OF LANSINGBURG, NEW YORK.

ELECTRIC ALARM-CLOCK.

SPECIFICATION forming part of Letters Patent No. 351,746, dated November 2, 1886.

Application filed August 30, 1886. Serial No. 212,188. (No model.)

To all whom it may concern:

Be it known that we, FRED E. DERRICK and SOLOMON C. BROTT, citizens of the United States, residing in the village of Lansingburg, 5 in the county of Rensselaer and State of New York, have jointly invented certain new and useful Improvements in Electric Alarm-Clocks, of which the following is a specification, reference being had to the accompanying 10 drawings.

The general objects of our improvements are to furnish a clock having mechanism for operating an alarm at a predetermined time with electric contacts and means for causing 15 the action of the winding-shaft of the alarm-operating mechanism in running down to establish electric connection between said contacts, and thereby close an electric circuit embracing said contacts, an electric source, and 20 an electro-magnetic alarm, to provide means for readily establishing and breaking electric connection between said electric contacts of the clock and the terminal conductors of an electric circuit embracing an electro-magnetic 25 alarm and electric source, and to provide means by which the winding-shaft of the alarm-operating mechanism of the clock can be caused to either establish or not establish electric connection between said electric contacts when 30 the winding-shaft runs down.

In the aforesaid drawings, Figure 1 represents the front side of a mechanical alarm-clock, an electric source or galvanic battery, and a self-acting electro-magnetic alarm, each 35 of a kind common in market, all connected together by electric conductors and embodying one form of our invention. Fig. 2 is an elevation of the rear side of the clock shown in Fig. 1, with one form of a portion of our invention 40 applied thereto; and Fig. 3 shows on a larger scale parts of the same clock and its support in elevation and in partial section at the line zz in Figs. 1 and 2, as viewed in the direction of the arrow y . Fig. 4 is an elevation of the 45 rear side of the same clock shown in Figs. 1 and 2, with modified parts of our invention applied thereto, and Fig. 5 shows on a larger scale parts of the same and a partial section at about the line xx in Fig. 4, viewed in the direction of the arrow w . Fig. 6 shows a portion 50 of the rear side of the same clock with

modified parts of our invention. Fig. 7 represents the rear side of another mechanical alarm-clock of a common kind with one form of a portion of our invention applied to the 55 clock and Fig. 8 shows on a larger scale a sectional elevation of parts of the same at about the line vv in Fig. 7 as seen in the direction of the arrow u . Fig. 9 shows the rear side of another mechanical alarm-clock of a common 60 kind with another form of a portion of our invention, and Fig. 10 shows a part of the same on a larger scale, viewed in the direction of the arrow t . Fig. 11 shows a part of the rear side of the alarm clock represented in Figs. 1 65 and 2, with modified parts of our invention.

A is the metallic case of the clock.

B represents a suitable galvanic battery or electric source.

C is an electro magnetic alarm, which will 70 continue in action while supplied with a suitable electric current, and can be of any such well-known self acting kinds.

The clock, electric source or battery, and electro-magnetic alarm can be close together, 75 or at any desirable distances apart, and are to be connected together by any suitable electric conductors, as b .

C' is a common switch or button, by which the electric circuit can be conveniently broken 80 and closed by hand.

D is the usual winding-shaft of the alarm mechanism, which can be of any ordinary or suitable kind, having an hour-circle and index and retaining and releasing parts, the same as 85 in the common and well-known mechanical alarm-clocks. The shaft D has a laterally-projecting metallic key, arm, or part, E , by which that shaft and the alarm mechanism are wound up by hand, as usual. When the alarm mechanism and winding-shaft run down, the shaft 90 and its key or arm turn in the direction of the arrow s .

To provide means for causing the action of the winding-shaft of the alarm mechanism to 95 close an electric circuit when that shaft runs down, or is stopped in its running-down movement, we furnish the clock with a stop, against which the key or arm on the winding-shaft shall strike and be arrested with the shaft in 100 running down, and with two electric contact-pieces, one insulated from the other and so ar-

ranged in respect to the winding-shaft with its key or arm that when they are arrested in running down by said stops, electric connection shall be thereby established between the 5 two electric contact-pieces in any manner, substantially as hereinafter set forth. The metallic key or arm E on the winding-shaft D can serve as one of said electric contacts, and then has electric connection with the clock-case A 10 by the metallic shaft D and the metallic gearing-frame, which supports the shaft and is secured in metallic contact with the case, as usual in such clocks.

F is the other electric contact-piece, which 15 is mounted on the case A, and is insulated therefrom, as indicated by the heavy black parts r, and is thus insulated from the key or contact-piece E on the winding-shaft when it is suitably wound up, as shown by full lines in 20 Figs. 6, 7, 9, and 11, and by dotted lines in Figs. 2 and 4.

In Figs. 2, 4, 7, and 9 the contact-piece F serves as a stop, against which the part E on the winding-shaft D strikes, and is stopped in 25 its running-down movement, and thereby establishes electric connection between the two contact-pieces.

In Fig. 11 a metallic spring contact-piece, e, 30 is secured to and in metallic connection with the case A, and extends between the insulated contact F and the arm E on the winding-shaft. When the shaft is wound up suitably, the part E is away from the spring part e, which is then away from the part F, as shown in full lines. 35 When the alarm mechanism of the clock is released and the winding-shaft D runs down, the part E of the shaft strikes against the spring-piece e and presses and holds it against the part F, and is thereby stopped in its running-down movement, and thus by its action 40 establishes electric connection between the contact-pieces F and e.

In Fig. 6 f is a metallic spring-piece, which is secured to and insulated from the case A, 45 and is separate from the insulated part F on the case. When the shaft D is suitably wound up, the part E on the shaft is away from the parts f and F, as shown in full lines. When the shaft is released and runs down, the 50 metallic part E first meets and bends the spring f, and next, while in contact with the spring, comes in contact with and is stopped by the part F, and thus establishes electric connection between the parts E and f, and between the parts 55 E and F, and between the parts F and f. By having the spring f sufficiently stiff it will stop the running-down movement of the part E, so as to establish electric connection between the parts E and f only. Upon removing 60 the part f the part E will be arrested by and held against the part F, so that electric connection will then be established between the parts E and F only.

To provide means for readily connecting 65 the two terminal conductors of an electric circuit embracing an electric source and an elec-

trical alarm with the aforesaid two electric contacts on the clock, we secure upon the metallic clock-case two attachments which are respectively adapted to receive and form electric connection with the two terminal conductors, and have one of said attachments in electric connection with the clock-case and with one of the two electric contacts, and the other attachment insulated from the case and in electric connection with the other of said electric contacts.

In the drawings one such attachment, G, is shown secured to and in metallic connection with the clock-case, and thereby in electric 80 connection with the contact-piece E or e, as hereinbefore specified, and the other attachment, H, is shown secured to and insulated from the case by the parts r, and in metallic connection with the contact-piece F, which is 85 secured to that attachment.

In Figs. 4 and 9 the attachments G and H are like common binding-posts, and are adapted to receive and clamp fast the wire or pin-form terminals, as p q, of the electric-circuit 90 conductors.

In Fig. 4 the parts G and H are shown arranged so that the clock can be thereby suspended from the conductor terminals.

In Figs. 1, 2, 3, 6, 7, and 11 the attachments 95 G H are in the form of eyes, rings, or hooks g h, by which the clock can be freely suspended, as shown in Fig. 1, from two conductor terminals in the form of pins or hooks p' q', Figs. 1 and 3, secured at a suitable distance 100 apart to and projecting from an insulating-support, I, so that electric connection shall be instantly established between said terminals and the electric contacts of the clock by merely hanging up the clock by its said ring or 105 hook attachments from the correspondingly-spaced conductor terminals, as indicated in Figs 1 and 3.

When the terminal conductors of the electric circuit through the battery B and electric 110 alarm C are respectively connected with the attachments G and H, which are respectively in metallic connection with the contact-pieces E, or e and F, in the clocks represented in Figs. 2, 4, 6, 7, 9, and 11, the circuit will be completed 115 when the winding-shaft D runs down, and thereby moves and holds its part E in contact with the part F in Figs. 2, 4, 6, 7, and 9, or the part e in contact with the part F in Fig. 11. When the circuit terminals are connected 120 with the attachments G and H' in Fig. 6, the circuit will be completed when the shaft runs down and its part E is stopped by the part F or f and in contact with the part f in metallic connection with the attachment H'; and when 125 the circuit terminals are connected with the attachments H and H', Fig. 6, the circuit will be completed when the winding-shaft runs down and its metallic part E is stopped by and in contact with the parts F and f. When the 130 circuit is thus closed through the battery and electric alarm by the action of the winding-

shaft of the alarm mechanism when it runs down, the electric alarm will continue to act until the battery becomes too weak to operate the alarm, or until the circuit is broken, which 5 breaking of the circuit can be conveniently accomplished by hand by means of the switch C' in circuit, and preferably away from the clock and near the electric alarm. Commonly, the electric alarm and switch will be in the 10 sleeping-apartment and the clock in a distant room. The circuit is to be left open at the switch until, and there closed by hand when, the winding-shaft of the alarm mechanism shall be by hand turned back or wound up 15 a portion of a revolution by the key or part E, and retained by the alarm mechanism of the clock away from the part F, and ready to be released to run down at a predetermined time indicated by the alarm-setting dial and 20 index on the clock.

When the electric alarm is used and operated in connection with an alarm-clock, as above described, the mechanical alarm of the clock may strike by its hammer J on the bell 25 K while the winding-shaft runs down to its stop or the hammer or the bell, or the bell and hammer may be absent from the alarm mechanism of the clock.

To provide means by which the winding-shaft of the alarm mechanism in running down 30 can be caused to stop and to close the electric circuit of an electric alarm, as above described, or to freely run down and cause an alarm to be sounded by the alarm mechanism of the clock 35 alone, we make one or the other, or both, of the two electric contact-pieces on the clock or the arm or key on the winding-shaft, suitably adjustable. For this purpose the contact-piece F in Figs. 2 and 3 can be turned to and fro and held 40 on its supporting-stem o, Fig. 3, from its position in full lines in Fig. 2 to its place in dotted lines at n, where it will be out of the path of the part E on the winding-shaft.

In Figs. 4 and 5 the attachment H with the 45 stop-piece F can be slid to and fro and secured on the rim m of the clock-ease from its place in full lines in Fig. 4 to where it is shown by dotted lines at l.

In Figs. 9 and 10 the key E is pivoted in 50 the head of the shaft D, and when turned up, as shown by dotted lines at k in Fig. 10, will pass over without touching the screw-stop F, which latter can be turned back, as indicated by dotted lines at j, so as to be out of the path 55 of the part E when it is turned down, as shown in full lines.

In Figs. 7 and 8 the part E is a double-headed screw-stem fitting in a female screw, through the head of the winding-shaft, so that 60 the part E can be turned with endwise movement to and fro from its extended position shown by full lines to its place in dotted lines at i in Fig. 7, where it will not come in contact with the part F in the rotation of the 65 winding-shaft.

In Figs. 6 and 11 the stem E fits and is mov-

able to and fro radially in a socket through the head of the winding-shaft, which is furnished with a clamp-screw, d, by which the part E can be fastened when extended, as shown in 70 full lines, and when retracted, as indicated by dotted lines, at e, so as to not touch either of the parts F, f, or e, as the winding-shaft revolves.

In Fig. 1 the electric conductors b are shown 75 connecting one pole of the battery B with one metallic clock-supporting pin or hook, q', and connecting the other pole of the battery with the electric alarm C, and that alarm with the hand-switch C', and the latter with the other 80 metallic clock-support, p'.

We claim as our invention—

1. An alarm-clock furnished with a stop for arresting the key or arm of the winding-shaft of the alarm mechanism in its running-down 85 movement, and with two electric contacts, between which electric connection is established by the action of said key or arm when arrested by said stop, substantially as set forth.

2. An alarm clock furnished with a stop for 90 arresting the key or arm on the winding-shaft of the alarm mechanism in running down, and with two electric contact-pieces of which one is moved and held in contact with the other by the key or arm as it is arrested by said 95 stop, substantially as set forth.

3. An alarm-clock furnished with a stop for arresting the key or arm on the winding-shaft of the alarm mechanism as it runs down, and with two electric contacts of which one is on 100 the winding-shaft, and is thereby moved and held in contact with the other contact-piece as the key or arm on the winding-shaft is arrested by said stop, substantially as described.

4. An alarm-clock furnished with a stop for 105 arresting the key or arm on the winding-shaft of the alarm mechanism as it runs down, and with two electric contacts of which one consists of said stop and the other consists of the key or arm on the winding-shaft of the alarm 110 mechanism, as set forth.

5. An alarm-clock having a metallic case and furnished with two electric contact-pieces, one on and carried by the winding-shaft of the alarm mechanism and in electric connection 115 with the case and the other mounted on and insulated from the case, and so arranged that the contact-piece on the winding-shaft shall be thereby carried and held in contact with the insulated contact-piece, and thereby stopped 120 as the winding-shaft runs down, substantially as set forth.

6. An alarm-clock having a metallic case, a key or arm on the winding-shaft of the alarm mechanism, a stop for arresting the key or 125 arm and winding-shaft in running down, two conductor attachments mounted on the case, one in electric connection with the case and the other insulated therefrom, and two electric contact-pieces, of which one is in electric 130 connection with the case and the other is secured to and in electric connection with the

insulated conductor attachment, and between which contact-pieces electric connection is established by the action of said key or arm when arrested by said stop, substantially as described.

7. An alarm-clock having a case furnished with two metallic rings or hooks by which the clock can be suspended, and of which one is insulated from the other, and two electric contacts which are respectively in electric connection with the two rings or hooks, and between which two contacts electric connection is established by the action of the alarm mechanism, substantially as set forth.

15 8. An alarm-clock having a key or arm on the winding-shaft of the alarm mechanism, a stop for arresting the key or arm in running down, two electric contact-pieces between which electric connection will be established by said key or arm when arrested by said stop, and said key, arm, or stop adjustable, so as to cause the winding-shaft with its said key or arm to be either arrested or not arrested by said stop, substantially as set forth.

25 9. An alarm apparatus embracing an electric source, an electro-magnetic alarm, an alarm-clock having a key or arm on the winding-shaft of the alarm mechanism, a stop by which the key or arm and winding-shaft will be arrested in running down, two electric contacts between which electric connection is established by the action of the key or arm when arrested by the stop, and electric conductors connecting the electric source, electro-magnetic alarms, and said two electric contacts, substantially as described.

35 10. An alarm apparatus embracing an electric source, an electric alarm, an alarm-clock having a key or arm on the winding-shaft of

the alarm mechanism, a stop for arresting the 40 key or arm in running down, two conductor attachments mounted on the case, one in electric connection with the case and the other insulated therefrom, two electric contacts, of which one is in electric connection with the 45 case and the other is secured to and in electric connection with the insulated conductor attachment, and between which two contacts electric connection is established by the action of said key or arm when arrested by said stop, 50 and electric conductors connecting the electric source, electric alarm, and said two conductor attachments, substantially as set forth.

11. An alarm apparatus embracing an alarm-clock having a case furnished with two 55 metallic rings or hooks by which the clock can be suspended, and of which one is insulated from the other, and with two electric contacts which are respectively in electric connection with the two rings or hooks, and between which two contacts electric connection is established at a predetermined time by the action of the alarm mechanism of the clock, two insulated metallic pins or hooks from which the clock is detachably suspended by 60 said rings or hooks on its case, an electric source, an electric alarm, and conductors connecting the electric source, electric alarm, and the two pins or hooks from which the clock is suspended, substantially as described.

In testimony whereof we heremunto set our hands, in the presence of two subscribing witnesses, this 27th day of August, 1886.
